UNITED STATES PATENT OFFICE.

WILLIAM L. SAXER, OF DUSHORE, PENNSYLVANIA.

BOX LID OR COVER HOOK.

Application filed January 4, 1924. Serial No. 684,344.

To all whom it may concern:

Be it known that I, WILLIAM L. SAXER, a citizen of the United States, residing at Dushore, in the county of Sullivan and 5 State of Pennsylvania, have invented certain new and useful Improvements in Box Lid or Cover Hooks, of which the following is a specification.

This invention relates to box lid or cover 10 hooks and it consists in the novel features hereinafter described and claimed.

An object of the invention is to provide a hook especially adapted to be attached to the cover of a rough box, used by under- 15 takers, and permits the use of a strap to lower the cover in place whereby the cover is properly positioned without requiring an attendant to descend into the grave. The hook is easily and quickly attached to the 20 lid of the box and the straps which are used in conjunction with the hook are passed through the hook and may be easily removed from the hook when the lid is in position upon the box. The hook is strong 25 and durable, easy to manufacture and inexpensive in production.

The hook consists of a single piece of iron wire having a straight intermediate section and parallel side sections merging with the 30 ends thereof. The side sections have loop corner portions and straight body and end portions the end portions having pointed extremities adapted to be driven in the edge portion of the box lid.

35 In the accompanying drawing—

Figure 1 is a perspective view of the hook.

Figure 2 is an edge elevational view of the same.

40 Figure 3 is a side elevation of the same.

As illustrated in the accompanying drawing the hook is formed from a single piece or length of wire, or metal, preferably soft iron. The hook consists of an intermediate 45 straight section 1 merging at its ends into side sections. The side sections are of the same shape and dimensions and a description of one will suffice. Each side section has a curved portion 3 which joins with the intermediate section, a straight side portion 2 depending from the curved portion and merging at its lower end with a loop 4. The loop 4 is not a complete loop but is open at one side as shown. The loop 50 merges with a straight end portion 5 which is chamfered at its end forming a pointed 55 extremity 6. The side sections of the hook are parallel with each other and lie in planes at right angles to the length of the intermediate portion 1, the portions 2 and 5 are 60 disposed at right angles to each other.

All portions of the side sections lie in the same plane and the loops 4 form corner portions of the hook and are disposed with portions projecting beyond the outer lines 65 of the portions 2 and 5.

In practice the pointed ends of the portions 5 are driven in the edge portions of the box cover and the lowering strap is passed through the hook and wrapped about 70 the portion 1 in a usual manner. The box cover is lowered into the grave and the loop portions 4 will encounter the edges of the box and guide the cover into proper position upon the upper edges of the box preparatory for securing the same in a usual manner. After the lid is lowered and positioned one end of the strap is cast off and the strap is pulled up from the hook in a 75 usual manner. The curved portions 3 dispose the intermediate portion 1 directly above or within the lines of the edges of the lid or toward the same so that the edges of the lid when being lowered will not come in contact with the walls of the grave and 80 knock the dirt into the coffin box.

Having described the invention what is claimed is—

1. A box lid hook formed from a single piece of wire having an intermediate 90 straight section and parallel side sections at the ends thereof, the portions of the side sections being of the same form and dimensions, each side section having a curved portion which merges with an end of the intermediate section and a straight body portion merging with said curved portion, a loop portion merging with the body portion and a straight end portion merging with the loop portion and having a pointed 95 extremity.

2. A box lid hook formed from a single piece of wire having an intermediate straight section and parallel side sections at the ends thereof, the portions of the side sections being of the same form and dimensions, each side section having a curved portion which merges with an end of the intermediate section and a straight body portion merging with said curved portion, a loop portion which is open at one side merging 105 with the body portion and a straight end 110

portion merging with the loop portion and having a pointed extremity.

3. A box lid hook formed from a single piece of wire having an intermediate straight section and parallel side sections at the ends thereof, the portions of the side sections being of the same form and dimensions, each side section having a curved

portion which merges with an end of the intermediate section and a straight body portion merging with said curved portion, a loop portion merging with the body portion and a straight end portion chamfered at its end to provide a pointed extremity.

In testimony whereof I affix my signature.

WILLIAM L. SAXER.
